(57) **CLAIM**

I claim the ornamental design for a tool for removing adhesive from hair extension weft.

DESCRIPTION

FIG. 1 is a perspective view of a tool for removing an adhesive from a hair extension weft, showing my new design;

FIG. 2 is a top plan view thereof;

FIG. 3 is a bottom plan view thereof;

FIG. 4 is a right side elevational view thereof, the left side being a mirror image;

FIG. 5 is a front elevational view thereof;

FIG. 6 is a rear elevational view thereof;

FIG. 7 is a perspective view of the tool in an open configuration;

FIG. 8 is a perspective view of the tool, with a roll of a fabric material incorporated therein; and,

FIG. 9 is a perspective view of the tool in an open configuration, with a roll of a fabric material incorporated therein. The broken lines are for illustrating unclaimed portions of the tool. The broken lines form no part of the claimed design. The appearance of any portion of the tool between break lines forms no part of the claimed design.
